CHILD'S VEHICLE

Joseph E. Scanland, Des Moines, Iowa., assignor
to New Monarch Machine & Stamping Company, Des Moines, Iowa, a corporation

Application February 1, 1950, Serial No. 7,618

Term of patent 14 years

(Cl. D34—15)

To all whom it may concern:

Be it known that I, Joseph E. Scanland, a citizen of the United States, residing at Des Moines, in the county of Polk and State of Iowa, have invented a new, original, and ornamental Design for a Child's Vehicle, of which the following is a specification, reference being had to the accompanying drawing, forming a part thereof.

Fig. 1 is a side elevational view of a child's vehicle, showing my new design;

Fig. 2 is a front elevational view thereof;

Fig. 3 is an elevational view of the side opposite that shown in Fig. 1;

Fig. 4 is a rear elevational view thereof; and Fig. 5 is a top plan view thereof.

I claim:

The ornamental design for a child's vehicle, substantially as shown.

JOSEPH E. SCANLAND.
